Inventor.
Joseph D. Porter

UNITED STATES PATENT OFFICE.

JOSEPH D. PORTER, OF HARRISBURG, PENNSYLVANIA.

ILLUMINATED OILING-CAN.

SPECIFICATION forming part of Letters Patent No. 548,616, dated October 22, 1895.

Application filed December 11, 1894. Serial No. 531,533. (No model.)

To all whom it may concern:

Be it known that I, JOSEPH D. PORTER, a citizen of the United States, residing at Harrisburg, in the county of Dauphin and State of Pennsylvania, have invented a new and useful 5 Illuminated Oiling-Can, of which the following is a specification.

My invention relates to improvements in illuminating oiling-cans or spouted feeders; 10 and the objects of my improvement are to supply light in oiling parts of machinery and oil from the feeder independent of or in conjunction with the light. I obtain these objects by the means illustrated in the accompanying drawings.

Figure 1 presents a full side view of the can with open section; Fig. 2, a view of cross-section; Fig. 3, a full view of front rim and spout in vertical position; Fig. 4, a cross-section disclosing lamp, protection-wall, and burner; Fig. 5, a section of feeder, swivel-valve, and spout; Fig. 6, a section of spouted feeder and swivel-valve; Fig. 7, a section of oil-reservoir, lamp compartment, and feeder. 25 Letters refer to similar parts throughout the several views.

The base A and the cylindrical portion O are divided into two compartments by a transverse partition K, forming an oil-reservoir Z 30 and lamp-compartment.

In top of reservoir is an opening D, through which the reservoir is filled. In the base of the lamp-compartment is a lamp having a longitudinal groove in its bottom, allowing it to span a feeding-tube H, which connects the bottom of the oil-reservoir with the swivel-spout of I.

To the back of the cylindrical portion, which is somewhat inclined, is fastened the 40 handle F, the relative positions of the handle F and air-vent E being such that the air-vent may be closed by the thumb of the operator when desired to stop the flow of oil from the spout of I.

45 In the side of the lamp-compartment is an opening which permits the lamp to be removed and which is closed by a sliding door B, having a slot near its lower edge, into which the handle D of wick-adjuster passes. The 50 door B slides in two guideways M, which are fastened to the sides of the can.

In the top of lamp-compartment is a chimney covered by hood C. The front of the cylindrical portion is closed by lens J and a perforated rim surrounding the lens. The 55 feeding-tube H terminates in an inclined branch tube L, which serves as a socket for the plug N, which is provided in one end with an internally-threaded opening, into which the end of the spout I is screwed. The plug 50 N is provided with a bore Y, which forms a direct continuation of the opening in the tube H, but is at an angle to the axis of rotation of the plug, forming a knuckle-joint, so that when the spout is in a pouring position the 65 opening Y registers with the opening of the tube H and permits the flow of the oil, as shown in Fig. 5. When not in use, the spout I is swung around on the spindle N as an axis until it comes into a vertical position, as 70 shown in Fig. 6, when the opening no longer registers with the tube H, and the flow of oil is thus cut off.

I am aware that prior to my invention illumination oiling-cans had spouted feeders. I 75 therefore do not claim, broadly, the entire combination.

What I do claim as my invention, and desire to obtain by Letters Patent, is—

The combination of an oil reservoir in front 80 of which is a dividing wall separating the reservoir from a lamp compartment and a lens in the wall of said compartment, a base above which is a cylindrical body O, a handle F, a feeding tube H in said base passing into the 85 oil reservoir; a lamp having a groove in the bottom thereof which spans the tube H, the lamp occupying the base of the lamp compartment, a sliding door having a slot for handle of wick adjuster D; an air vent E on 90 top of oil reservoir; a perforated rim surrounding the lens and a spout connected to the feeding tube H by a knuckle joint by which is formed a swivel revolving valve and cut off, substantially as described.

JOSEPH D. PORTER.
